UNITED STATES PATENT OFFICE

2,513,175

SANITARY PUMP

Roger W. Hood, Norwood, Mass., assignor to
 United American Soda Fountain Corporation,
 Watertown, Mass., a corporation of Massachusetts

Application August 7, 1947, Serial No. 766,927

3 Claims. (Cl. 103—178)

1

This invention relates to dispensing pumps, and is particularly concerned with that type of pump commonly used in dispensing beverages at soda fountains. The pump in the present application, while ordinarily used with beverages, nevertheless can be used with equal facility in the dispensing of any kind of liquid.

Pumps used for beverages, particularly for syrups and milk, must in the interest of sanitation be cleaned at short intervals. In the pumps heretofore used in this field, the constructions are of such character that adequate cleaning is a distinctly difficult job. This is due to the fact that a substantial amount of time is required for the dismantling and reassembly, which must be undertaken if the unit is to be thoroughly cleaned. Furthermore, the complexity of the parts in themselves makes thorough cleaning a real problem.

Municipalities generally today are setting higher standards of cleanliness in public eating and drinking places. In the light of these new requirements, the pumps of the prior art are now considered by the trade as incapable of meeting the new requirements that demand rapid and more thorough cleaning.

Accordingly, one of the objects of the present invention is to provide a construction which may be so easily disassembled and cleaned that the users thereof will not find themselves reluctant to take the unit apart and to perform the cleaning operation. In many localities official inspection is frequently made. The pump disclosed herein makes it possible with minimum inconvenience and loss of time to maintain the required sanitary standards.

A further object of the invention is to provide a construction so designed that all parts may be readily reached with brushes commonly used for cleaning purposes. Another object of the invention is to provide a dispensing pump which permits easy and quick removal of the piston from the cylinder, so that all parts of the cylinder and piston may be easily cleaned.

Another object of the invention is the provision of a delivery tube and nozzle so constructed that all interior pipe sections can be easily and quickly reached throughout their entire lengths by the use of a pipe or tube cleaning brush.

A further object of the invention is the pro-

5 vision of closure means at the upper end of the delivery tube and at the outer end of the nozzle of such character that upon removal, all those parts which come into contact with the liquids will have smooth plane or curved surfaces which may be very easily cleaned. While this construction contemplates the use of screw threads in a preferred form, nevertheless, the screw threads are so located as to be entirely out of range of contact with the liquid, so that the inadvertent failure to clean the thread will not be dangerous.

10 While the invention in the accompanying drawings and following description is disclosed as having a particular pump handle arrangement, it will be understood that the angularity of radial direction of the pump handle may be varied in accordance with the requirements of any given installation.

15 The invention will be more clearly understood as the description proceeds with the aid of the accompanying drawings, in which:

Fig. 1 is a side elevation of the pump, part being in section and part a side elevation. The parts have been broken away through a horizontal section to reduce the height of the drawing.

20 Fig. 2 is a fragmentary elevation similar to Fig. 1, illustrating the valve action during the descent of the piston.

25 In accordance with common practice, the pump assembly is mounted on a container cover plate 2, shaped to close properly the top of the container with which the pump is used and to provide a sufficiently rigid support for normal operation.

30 Descending from cover plate 2 is a supporting side rod 4, rigidly mounted on the under side of the plate in any convenient manner. To the side of the lower end of this rod is secured, usually by soldering, an inverted open-ended cylinder 6, closed at its top by a disc 8. This disc has two holes through it, one axially located at 10 and the other at the edge at 12. Extending upwardly from opening 12 to the under side of plate 2 is a delivery tube 14 which in the present disclosure terminates in an internally threaded bushing 16.

35 Into the upper end of this bushing is threaded the lower extension 18 of nozzle 20. This nozzle has a vertical portion 21 with a bore 22, the bore

being an extension of and in alignment with delivery tube 14. A diagonally upwardly extending nozzle portion 20, having a bore 24 connecting with bore 22, leads away from portion 21. Near the upper end of bore 24 is a downwardly directed tip 26, having a bore 27 that leads to the exterior from bore 24.

The pump mechanism comprises the cylinder 6, a piston 28 having a port 29, valve 30 that closes port 29, and piston rod 32 extending upwardly through the opening 10 which fits closely thereto. The operating mechanism for the piston rod may be any conveniently arranged lever. In the form shown, there is a lever 34 pivoted at 36 on a forked support 35, with one arm 38 connected to the upper end of piston rod 32 by a link 40. The remote end of lever 34 has an expanded area 42 against which the operator's hand may press without discomfort.

A spring 44 coiled about pivot 36 has its terminal end 46 hooked over lever arm 38 and continuously urging the lever to its downmost position, so that when the pump is not in use piston 28 will be at the bottom of its stroke, as shown in Fig. 1. Upward movement of piston rod 32 is limited by engagement of valve 30 with the closed upper end 8 of cylinder 6.

As shown in the drawing, the piston rod 32 is straight and smooth throughout its entire length. The upper end of the piston rod is slidably positioned in a bushing mounted on cover plate 2, as shown. Link 40 which connects the upper end of piston rod 32 to arm 38 may be removed from both elements by withdrawal of the two transversely extending pins, one of which passes through the upper end of piston rod 32 and the other through the lower end of arm 38.

When link 40 has been disconnected from piston rod 32, it is obvious that the piston rod and its associated parts, namely, piston 28 and valve 30, may be dropped downwardly out of cylinder 6 to be completely withdrawn from the supporting structure.

Another important feature of the invention is the construction designed to help insure cleanliness through ease of cleaning the closures at the upper end of the delivery tube and the upper end of the nozzle. These two closures are shown as being identical, although obviously the size of the respective parts might be varied.

The closure at the upper end of bore 22 of the nozzle extension of tube 14 comprises a cylindrical plug 54 having its lower end of a diameter that will fit snugly within bore 22. The central portion of the plug is of greater diameter, as at 56, providing thereby lower and upper horizontal shoulders. The upper portion of the plug above the upper shoulder is of reduced diameter, which for convenience may be made the same as that of the lower end. The lower shoulder of portion 56 fits snugly against the upper end of bore 22, and the plug is held tightly in position by a collar 58 having an inturned flange 60 which engages the upper shoulder. Collar 58 is in screw threaded engagement with portion 21 as at 59. By screwing collar 58 downwardly, plug 54 will be brought into liquid-tight engagement with the upper end of bore 22, thereby effectively closing the top of the delivery tube.

The construction of the plug and collar at the outer end of nozzle 20 is the same as that just described, and accordingly, the parts have been indicated by the same numbers.

Since plug 54 has its outer surface cylindrical and smooth and the ends are flat, and, further,

since the ends of the portion 21 and nozzle 20 against which the lower shoulders of the enlarged parts 56 rest are likewise smooth and flat, it is obvious that the cleaning of these parts will be greatly facilitated. The liquid to be dispensed will come in contact with one end only of each plug when the pump is in use. It is believed that this arrangement entirely eliminates any possibility of contamination by the thread surfaces 59, should the latter be improperly cleaned.

While collar 58 is attached to the delivery tube and nozzle by means of screw threads, still it will be understood that equivalent means could be used without departing from the invention.

The delivery tube and nozzle for convenience have been made in two parts, with each part having a straight run therethrough to facilitate cleaning. It will be understood, however, that the two could be made as a single unit with a single end closure, provided the curvature of the entire tube will permit passing a cleaning brush the entire length thereof.

The operation of the pump is as follows. Prior to movement of the lever 34, piston 28 will normally be in the position shown in Fig. 1, as piston rod 32 has been moved downwardly to that position by spring 44. Cylinder 6, being near the bottom of the container, is, of course, completely immersed in the liquid. The area 50 within cylinder 6 will be filled with liquid which has entered through the piston valve during the preceding downward stroke. When the operator moves lever 34 to the left, as shown in dotted line position, piston 28, with valve 30 closed, will move upwardly to drive liquid from the cylinder up through delivery tube 14 and out through tip 26 of the nozzle. The maximum amount of liquid that can be delivered on a single stroke is substantially the volume of cylinder 6 contained above the piston.

Upon release of lever 34, spring 44 will drive piston 28 downwardly, and in so doing the pressure of the liquid on the underside of piston 28 will force valve 30 to the diagonally cocked position shown in Fig. 2. Valve 30 opens immediately upon the commencement of descent of piston 28, thereby permitting liquid to flow through the port 29 of piston 28 and past valve 30 into the area 50 above the piston.

The opening of valve 30, occurring simultaneously with the beginning of the descent of piston 28, insures that area 50 will be filled with liquid, regardless of the position at which the downward movement of piston 28 is commenced. When the piston 28 has descended to bottom position, the level of the liquid in delivery tube 14 will be substantially that of the liquid in the container. Thus, only a small movement of lever 34 is required on a new stroke before the liquid flows from the nozzle.

The eccentric location of port 29 and the tilting of valve 30 which jams on piston rod 32 during the down stroke is an important feature of the invention. This construction not only provides for closure of the valve substantially simultaneously with the commencement of the upstroke of the piston, but also causes the valve to operate in a uniform manner on the downstroke.

When the piston starts downwardly, the immediate cocking and jamming of valve 30 on piston rod 32 insures that the valve will maintain a constant position regardless of the rate of descent and will be in position to close immediately upon the commencement of the next delivery stroke,

whether that stroke be commenced after complete or partial downward movement of the piston.

The degree to which the valve 30 can tilt on piston rod 32 is determined by the diameter of the centrally located opening through the valve and the thickness of the valve at the opening. These two factors obviously determine the distance between diametrically opposite portions of the periphery of the opening, and also the angularity of this distance with respect to the plane of the valve. If the centrally located opening remains of constant diameter, then increasing the thickness of the valve at the opening will increase the distance between the diametrically opposite portions but will decrease the angle through which the valve disc may rotate. Conversely if the thickness of the valve at the centrally located opening remains constant and the diameter of the opening is increased, the distance between the diametrically opposite portions of the periphery will increase and the angle through which the valve disc may be rotated will likewise increase.

If it is desired to maintain a constant maximum slanting angle of the valve, this may be done by adjusting the diameter of the opening to the thickness of the valve at the opening. In all cases, however, it is desirable that the extent of the valve opening be relatively limited so that closing of the valve will occur upon very slight upward movement of the piston at the commencement of the discharge stroke.

In further explanation of the foregoing, it is pointed out that if, for example, there was another port 29 located at 180° from the present port 29, then downward movement of the piston would result in valve 30 lagging behind as it gradually floated down through the liquid. That is to say, unless the valve 30 is positively carried down by the piston, it would lag behind the piston in varying amounts, depending on the rate of piston descent. Such lagging would cause variable amounts of liquid to be delivered if upward movement of the piston commenced before the valve had seated.

It may therefore be stated that the construction of the present valve provides for closure of the orifice coincidental with the beginning of upward piston movement, where the latter is actuated immediately following a downward stroke. Of course, it will be understood that if the piston has been allowed to come to rest, valve 30 will settle at once on the piston to close port 29, which condition will be present at the start of any subsequent delivery stroke.

While the invention has been described with reference to a preferred form, it is not to be limited thereby, but only by the appended claims.

I claim:

1. Piston and valve mechanism for use in a beverage pump comprising a cylinder open at one end, a piston rod having mounted thereon a circular disc forming a piston, said piston fitting closely within said cylinder and removable therefrom through said open end without modification of said cylinder, a passage through said piston, all of said passage being on one side of a diameter of said piston, a second disc forming a valve and resting on the top of said piston with the piston rod extending through a centrally located opening in said valve, said centrally located opening being larger than said piston rod, said valve being of less diameter than said piston but large enough to overlie said passage to close the latter, that

portion of the piston rod within said cylinder being straight and smooth, said valve movable upwardly to a slanting position under the influence of the pressure of fluid flowing upwardly through said piston passage against the under side of said valve, the movement of said valve along said piston rod being limited solely by engagement of diametrically opposite portions of the periphery of said opening against said piston rod, the distance between the said diametrically opposite portions of the periphery of said opening being controlled by the diameter of said centrally located opening and the thickness of said valve disc at said opening, said distance determining the angle of the maximum slanting position of said valve.

2. Piston and valve mechanism for use in a beverage pump comprising a cylinder open at one end, a piston rod having mounted thereon a circular disc forming a piston, said piston fitting closely within said cylinder and removable therefrom without modification of said cylinder, a passage through said piston, all of said passage being on one side of a diameter of said piston, a second disc forming a valve and resting on the top of said piston with the piston rod extending through a centrally located opening in said valve, said centrally located opening being larger than said piston rod, said valve being of less diameter than said piston but large enough to overlie said passage to close the latter, that portion of the piston rod within said cylinder being straight and smooth, the thickness of said valve at the periphery of said centrally located opening in relation to the diameter of said opening and the diameter of said piston rod being such as to limit upward movement of said valve caused by the pressure of fluid flowing upwardly through said piston passage against the underside of said valve to a slanting position not greater than an angle of thirty degrees to the plane of said piston, the aforesaid movement of said valve with respect to said piston and piston rod being controlled by the engagement of diametrically opposed portions of the periphery of said opening against said piston rod, the distance between the said diametrically opposed portions of the periphery of said opening being controlled by the diameter of said centrally located opening and the thickness of said valve disc at said opening, said distance determining the angle of the maximum slanting position of said valve.

3. Piston and valve mechanism for use in a beverage pump comprising a cylinder open at one end, a piston rod having mounted thereon a circular disc forming a piston, said piston fitting closely within said cylinder and removable therefrom without modification of said cylinder, a passage through said piston, all of said passage being on one side of a diameter of said piston, a second disc forming a valve and resting on the top of said piston with the piston rod extending through a centrally located opening in said valve, said centrally located opening being larger than said piston rod, said valve being of less diameter than said piston but large enough to overlie said passage to close the latter, said piston rod being straight and smooth throughout its entire length whereupon when said piston and piston rod have been removed from said cylinder through said open end, said valve may slide freely along the entire length of said piston rod, said valve when in operative position on said piston movable upwardly to a slanting position under the influence of the pressure of fluid flowing upwardly through said piston passage against the underside of said

valve, the movement of said valve caused by said flowing fluid being limited solely by engagement of opposed positions of the periphery of said opening against said piston rod, the distance between the said opposed portions of the periphery of said opening being controlled by the diameter of said centrally located opening and the thickness of said valve disc at said opening, said distance determining the angle of the maximum slanting position of said valve.
